UNITED STATES PATENT OFFICE.

THOMAS MALCOLMSON, OF OIL CITY, PENNSYLVANIA, ASSIGNOR OF ONE-HALF TO OCTAVIUS B. GOODWIN, OF SAME PLACE.

STEAM-GOVERNOR.

SPECIFICATION forming part of Letters Patent No. 289,427, dated December 4, 1883.

Application filed February 8, 1883. (No model.)

To all whom it may concern:

Be it known that I, THOMAS MALCOLMSON, a citizen of the United States, residing at Oil City, in the county of Venango and State of Pennsylvania, have invented certain new and useful Improvements in Steam-Governors, of which the following is a specification.

My invention relates to a governor designed for the purpose of controlling the supply of steam to the cylinder of an engine, in order that its speed of operation shall be uniform, the object being to control said supply of steam by devices which shall be as simple, sensitive, and practical as possible. In this instance I have adapted my invention for operation in connection with valves of that class known as "oscillating."

My invention consists in certain features hereinafter described, and specifically set forth 20 in the claims.

In the accompanying drawings, Figure 1 is a perspective, showing my governor upon a horizontal shaft secured to the valve-casing; Fig. 2, a longitudinal vertical section of the 25 same, but detached from the valve-casing; Fig. 3, a transverse section of the revolving disk, its spring-weights and surrounding disks; and Fig. 4 represents modifications of a governor's spring-weight constructed in accordance with 30 my invention.

Like letters refer to like parts in all the figures.

A represents the valve-chamber, which contains an ordinary oscillating valve, the chamber being supposed to be connected with any ordinary steam-chest to regulate the supply of steam thereto in the usual well-known manner.

B represents the bracket, secured in any suitable manner to one end of the valve-chamber, and it serving to support a shaft, C, seated in the apex of the arch of the bracket, and secured thereto by a nut, c. By this means the shaft is held rigidly in the bracket, and serves 45 as a support for the flanged disk D, and also for a second disk, E, rigidly secured to or formed integral with a sleeve, E', to which is rigidly secured the belt-pulley E''. The disks D and E are loosely journaled upon the shaft 50 C, and retained from longitudinal movement thereon by a nut, c', at the end of said shaft.

The shaft C is hollow throughout a portion of its length, sufficient in extent to serve as an oil-chamber for the sleeve E', perforations c'' being made in the walls of the chamber and filled with wooden plugs or fiber, the grain of 55 which is disposed lengthwise in the perforations, in order to conduct, by capillary attraction, the oil from the chamber through the perforations and against the inner or bearing surface of the sleeve. An elbow, C', is fitted to 60 the outer end of the oil-chamber, and is provided with an oil-cup, C''. The disk D is provided in this instance with a projecting arm, D', to which is adjustably secured the counter-balance D''. To the disk E are secured, in 65 this instance by flat arc-springs E'', suitably bent and conformed to its periphery, weights E', which, by said springs, are in this instance forced inwardly against the periphery of disk E. Friction-pads e are secured in dovetailed 70 recesses formed in the outer surface of the weights E'.

In an operative position the disk D incloses the disk E and its weights and springs, and projecting from its outer flat surface there is 75 a post, F, to which is rigidly secured an arm, F', projecting inwardly and secured rigidly to the valve-stem G by means of a pin, f, or otherwise.

Upon the opposite side of one branch of the 80 bracket-arch from that at which point the post F is located is another post, F'', projecting also from the disk D, to limit its oscillations within certain limits. The valve-stem has its extremity journaled centrally into the end of the 85 shaft C, and passes through a stuffing-box, G', projecting from the face-plate of the bracket B, as clearly shown in Fig. 2.

As thus far described, it will be seen that as motion is first given to the pulley E'' by the 90 usual governor-belt, the sleeve E' and disk E are rotated, and that this rotation is independent of disk D and has no effect upon the valve-stem, the valve secured thereto being retained open by the weight or counter-balance D'' 95 when the engine starts; but when the speed of rotation of the sleeve and its disk and the springs and weights E', secured thereto, as described, is sufficient to force or throw by centrifugal impulse said weights against the 100 retractive force of the springs and away from

the disk E, said weights come in contact with the inclosing-flange of the disk D, and communicate motion thereto, so as to partially revolve it, and thus lift the counter-balance 5 D^2 , and partly rotate the valve-stem by means of the rigidly-attached arm F', secured to post F, which arm and post move with the disk. By this means the valve is closed, the supply 10 of steam shut off, and the speed of the engine reduced. When so reduced sufficiently, the tension of the springs withdraws the weights from the flange of disk D, and the counter-balance D^2 restores said disk, post, and arm and the valve-stem to their original position. 15 The counter-balance D^2 is adjustably secured to the arm D', in order to regulate the amount of friction exerted by the springs upon the flange of disk D, so that more or less of the 20 said friction shall be necessary to operate the disk and valve-stem. It is readily seen that if the counter-balance is set near the disk less friction will be required to lift the counter-balance than when set a distance therefrom. By 25 this means exceedingly fine adjustment is secured, and a like sensibility in the governor, as constructed, to variations in the speed of the engine is attained.

It is apparent that many modifications or 30 variations in the mechanism of a governor constructed in accordance with my invention are within the scope of mechanical skill—as, for instance, instead of the flat arc-springs 35 conformed to the periphery of the disk E, arms h may be hinged to the periphery of the disk E and provided with frictional weights e^2 , retained from the disk D by retractible coiled springs.

Elliptical springs i, secured to the periphery 40 of the disk E, may be interposed between the flanges of the disks D and E, and weights secured to the outer leaf thereof. Coiled springs 45 may be secured to the inner disk and provided with radiating weights j, and adapted to slide in grooves therein and project against the flange of the outer disk. Furthermore, the disks may be in skeleton form—that is, comprising hubs, spokes, and a flange. If desired, one or more of said spokes may be hollow and a weight inclosed therein in the form of a piston, secured to the hub or spoke by a retractible spring. Other means may be employed 50 for lubricating the journals of the moving parts, and instead of the exterior counter-balance, D^2 , supported by a rigid arm to the disk 55 D, a strap or chain supported upon the periphery of the disk, and having a counter-balance secured thereto, may be employed, or a retractible spring may be secured to the arch B at one end and to the arm F' or post F or 60 F² at the other end, to take the place and perform the functions of the counter-balance. A helical spring placed between the disks D and

E, and having one end secured to each one of these disks, may also perform the same function. 65

The invention herein disclosed is an improvement upon the construction shown in a companion application filed by me and pending at the same time.

Having described my invention and its operation, what I claim is— 70

1. In a speed-governor for steam-engines, the combination of a shaft, a flanged disk loosely journaled thereon, connected to the valve-stem and inclosing a second disk, and interposed weights connected by springs to said inclosed disk, with a counter-balance, or its described equivalent, secured to the inclosing disk, and means for revolving the inclosed disk, substantially as described. 80

2. In a speed-governor for steam-engines, the combination of a shaft adapted to receive the end of the valve-stem, a bracket for its support, a flanged disk, D, journaled upon the shaft and provided with an arm connected to the valve-stem, and a stop-post, F², with a sleeve provided with a flanged disk, E, means for revolving the disk E, and weights connected to the flange of said disk, and adapted to be thrown therefrom by centrifugal impulse, substantially as specified. 90

3. In a speed-governor for steam-engines, the combination, with the valve-stem, of two flanged disks, one arranged within the other, interposed weights adapted to be forced by centrifugal impulse from one disk to the other, and a counter-balance, or its described equivalent, substantially as specified. 95

4. A steam-engine speed-governor consisting of a shaft carrying a disk provided with 100 weights retained by springs, having one end secured thereto and adapted to be thrown off by centrifugal motion, in combination with a surrounding disk to arrest the centrifugal momentum of said weights and by friction there-with reduce the speed of the disk and governor-shaft, substantially as and for the purpose described. 105

5. The combination of the hollow shaft C, perforated as described, wooden plugs e^2 , the elbow C', oil-cup C², sleeve E', and disk E, of a governor carrying weights secured to springs, substantially as specified. 110

6. The combination of the bracket B, shaft C, disks D and E, weights secured to springs 115 between said disks, and adjustable counter-balance D^2 , with the valve stem G and suitable connections, substantially as specified.

In testimony whereof I affix my signature in presence of two witnesses.

THOMAS MALCOLMSON.
